UNITED STATES PATENT OFFICE.

HENRI SCHNEIDER, OF CREUSOT, FRANCE.

GAS-CHECK FOR ORDNANCE.

SPECIFICATION forming part of Letters Patent No. 427,370, dated May 6, 1890.

Application filed January 30, 1890. Serial No. 338,653. (No model.) Patented in England November 13, 1889, No. 18,158.

To all whom it may concern:

Be it known that I, HENRI SCHNEIDER, a citizen of the Republic of France, and a resident of Creusot, Sôane et Loire, France, have 5 invented Improvements in Gas-Checks or Obturators for Breech-Loading Ordnance, of which the following is a specification.

This application for a patent relates to what may be termed a "composite" obturator, participating simultaneously in the properties of the Broadwell ring and of the plastic obturator, providing a perfect closure under any pressure, and enabling the breech-screw to be worked with the greatest ease. This composite obturator is illustrated in the accompanying drawings referred to in the following description.

Figure 1 represents in section an obturator applied to a movable breech with a movable 20 head C, free upon the stem A, attached to the breech-screw B. Fig. 2 represents the obturator applied to a movable breech with a movable head C, made in one with the stem A of the breech-screw B.

25 This composite obturator comprises a plastic ring or pad D, two flat washers R and S, two split rings E and E', and four elastic rings F F' G G' in one piece, the whole being interposed between the movable head C and the breech-screw B. The plastic ring D, composed of asbestos and mutton-fat in the usual proportions, is inclosed between the two washers R and S, one of which—the front one—is provided with split rings E and E'. The 30 washers R and S are made of any suitable metal; but preferably the front washer is of red copper and the back washer of steel. Their peculiarity lies in their being flat and presenting no rim or projection, either inside 35 or on the outside, except in the special case illustrated in Fig. 2, where the front washer follows the profile of the rounded part connecting the stem A to the movable head C. In this case the corresponding elastic ring G' 40 is dispensed with. The rings F F' G G' in one piece are of triangular or other section and are composed of cold-hammered red copper or any other metal possessing a high degree of elasticity. Their function is to support the external and internal edges of the 45 plastic ring or pad D. The outer rings are connected to the washers R and S by means

of a very shallow undercut groove which retains them freely in position. Between the obturator thus constituted and the sides or 55 surfaces of the breech-chamber a vacancy or small amount of play is provided to the extent of from about 0 mill 1 to 0 mill 2. The same amount of play is allowed between the obturator and the stem A. This arrangement 60 greatly contributes to ease the opening and closing of the breech. Under the influence of the pressure of the gases resulting from the combustion of the powder when a shot is fired the plastic ring D, being pressed between the 65 movable head C and the breech-screw, is slightly flattened and expands transversely. The expansion takes place externally toward the side of the breech-chamber and internally toward the stem of the movable head. It is 70 regulated by the internal pressure, and consequently prevents any escape of gases whatever. In expanding, the ring D carries with it in its movement the elastic rings F, F', G, and G', which are applied accurately against 75 the bore and against the stem, so as to prevent any exudation of plastic matter between the surfaces of the joint. When the pressure ceases, the elastic rings return to their original form and the play of from 0 mill 1 to 80 0 mill 2 reappears in the chamber and around the stem, thus enabling the breech to be opened with the same ease with which it was closed before firing.

In conclusion, it is evident that this composite obturator can be constructed of any sizes, so as to be applicable to breech-loading ordnance of any caliber.

I claim as my invention—

1. The composite obturator or gas-check for 90 the breech-screws of guns, said check consisting of two flat washers and an intermediate plastic ring, with rings at the joints to prevent exudation of the plastic material, all substantially as described.

2. The combination of the movable head and movable breech-screw of a gun with the composite obturator or gas-check between the 95 said head and screw, the said check consisting of two flat washers and an intermediate 100 plastic ring, with rings at the joints to prevent exudation of the plastic material, all substantially as described.

3. The composite obturator or gas-check

adapted to be placed between the movable head and movable breech-screw of a gun and on the stem, and consisting of two flat washers, an intermediate ring of plastic material, 5 elastic rings to make joints at the sides of the chamber, and similar elastic rings to make joints with the said stem and prevent exudation of the plastic material, all substantially as described.

10 4. The composite obturator or gas - check adapted to be placed between the movable head and movable breech-screw of a gun and on the stem, and consisting of two flat washers, an intermediate plastic ring, a split ring

or rings between the head and one washer, 15 elastic rings, each in one piece to make joints at the sides of the chamber, and similar elastic rings to make joints with the stem and prevent exudation of the plastic material, all substantially as described. 20

In testimony whereof I have signed my name to this specification in the presence of two subscribing witnesses.

HENRI SCHNEIDER.
